The ornamental design for a riding device, as shown and described.

DESCRIPTION

FIG. 1 is a front perspective view of a riding device according to an embodiment of our design;

FIG. 2 is a similar perspective view thereof, shown without the upright extension bars and seat for clarity of illustration;

FIG. 3 is a front view thereof;

FIG. 4 is a rear view thereof;

FIG. 5 is a top view thereof;

FIG. 6 is a bottom view thereof;

FIG. 7 is a right side view thereof;

FIG. 8 is a left side view thereof;

FIG. 9 is a front perspective view of a riding device according to a 2nd embodiment of our design;

FIG. 10 is a similar perspective view thereof, shown without the upright extension bars and seat for clarity of illustration;

FIG. 11 is a front view thereof;

FIG. 12 is a rear view thereof;

FIG. 13 is a top view thereof;

FIG. 14 is a bottom view thereof;

FIG. 15 is a right side view thereof; and,

FIG. 16 is a left side view thereof.

Throughout the various figures of the drawings, certain views may not be provided. The omission of a particular view is intended to convey that the element(s) depicted is/are plain and unornamented in that omitted view, or that the particular ornamental appearance in that view is simply not claimed.
